UNITED STATES PATENT OFFICE.

HARRY N. NEPELL, OF NEW YORK, N. Y.

HAT.

1,418,198.

Specification of Letters Patent. Patented May 30, 1922.

Application filed April 26, 1921. Serial No. 464,512.

To all whom it may concern:

Be it known that I, HARRY N. NEPELL, a citizen of the United States, and a resident of the city of New York, borough of Manhattan, in the county and State of New York, have invented a new and Improved Hat, of which the following is a full, clear, and exact description.

This invention relates to headwear and has particular reference to an outing hat especially designed for use in ball parks, race tracks, or other similar public places of amusement.

The primary object of the present invention resides in the provision of a simple and inexpensive hat which is designed to be sold to the public at a minimum price, or distributed as a medium of advertising.

Another object in view is to provide a hat which is constructed in such a manner as to render the same capable of fitting almost any size or shape of head.

A further object in view is to provide a novelty hat which is especially useful in the hot weather, which will effectively shade the head and face of the wearer, and which will be cool and comfortable when in use.

A still further object in view resides in the provision of a hat which employs a minimum number of parts, rendering the same easy to assemble and capable of folding and nesting into a small space for the purpose of shipment of transportation.

With the above recited and other objects in view the invention resides in the novel construction, combination and arrangement of parts set forth in the following specification, pointed out in the appended claims and illustrated in the drawings, in which—

Figure 1 is a perspective view of the hat illustrating the same in applied position.

Fig. 2 is a plan view of the crown or top member removed.

Fig. 3 is a similar view of the brim prior to its assembly with the crown.

Fig. 4 is a side elevation of the same in assembled or set-up position.

Fig. 5 is a similar view of the same in collapsed or folded position.

Fig. 6 is a detail fragmentary sectional view taken approximately on the line 6—6 of Fig. 3.

Referring to the drawings by characters of reference, the hat comprises a brim 10 and a crown or top 11, which is supported in superposed spaced relation from the brim

by means of bendable tongues 12 which are formed as an integral part of the brim. The top or crown is of substantially oval formation and is preferably constructed 60 from relatively stiff paper or cardboard, provided at its front and rear ends with transverse slits 13 which are designed to receive the heads 14 at the free extremity of the tongues 12, connected thereto by the reduced necks 15. The heads 14 in assembling the hat are preferably inserted through the slits 13 after which the reduced necks 15 lie within the slotted portions. The side tongues 12 are of like construction, having 70 heads 14 at their free extremities provided with the reduced necks 15. Inasmuch as the side tongues 12 must be disengaged in order to permit of the folding or collapsing of the crown against the brim, it is desirable to 75 provide the side slits 16 with entering mouths 17 which establish communication between the side slits 16 and the outer edge of the crown. In order to render the hat applicable to heads of various sizes and con- 80 tours the front and rear inner edges of the brim are radially slotted as at 18 to provide readily bendable tongues 19 which are transversely scored as at 20. By this arrangement the wearer, by forcing the brim over 85 his head, will effect the upward bending of the tongues 18 at the scoring, which affords a close frictional contact of the inner edge of the brim with the head.

In the manufacture of the hat the brim 90 and the tongues 12 and 19 are stamped from a single sheet of material, while the crown or top 11 is stamped from another sheet of material. The brims and crowns may be shipped in quantities in their flat condition, 95 as illustrated in Figs. 2 and 3. In selling or disposing of the hats, the vendor will engage the front and rear tongues 12 with the crown and fold the same downwardly there-over substantially as illustrated in Fig. 5. 100 The purchaser upon receiving the hat is then only required to lift the crown and engage the side tongues 12 with the slits 16. It will thus be seen that a simple and inexpensive hat, adapted to be sold at a minimum price 105 or disposed of as an advertising medium, is provided which affords ample protection against the sun and heat, and which is capable of folding to occupy a minimum amount of space.

While there has been illustrated and described a single and preferred embodiment

of the invention, no limitation is necessarily made to the precise structural details, as it is to be understood that variations and modifications which properly fall within the scope of the appended claims may be resorted to when found expedient.

Having thus described my invention, what I claim is:

1. A novelty hat comprising a crown and a frame having a head receiving opening, and circumferentially spaced supporting strips secured to the brim having disengageable connection at their free ends to the crown to constitute a means for connecting the crown to the brim whereby to permit of the folding of the crown against the brim upon disengagement of certain of the supporting strips from the crown and bending the remaining strips.
2. A novelty hat including a brim and a crown, said brim having a head receiving opening therein, and integral vertically dis-

posed circumferentially spaced supporting strips having disengageable connection at their free ends to the crown and serving as a means for connecting the crown with the brim to permit of the folding of the crown against the brim upon disengagement of certain of the supporting strips from the crown and bending of the remaining strips.

3. In a novelty hat, a brim having an opening therethrough and slits extending radially from the inner edges of the brim forming bendable tongues to afford means for adjusting the opening to the head, a crown, and means provided on the brim for supporting the crown therefrom in superposed spaced relation with respect thereto, said means comprising slotted portions in the crown, and bendable strips carried by the brim, the free extremities of which are engageable in said slits.

HARRY N. NEPELL.
